CLAIM

The ornamental design for a small shelf bracket, as shown and described.

DESCRIPTION

FIG. 1 is a top perspective view of a small shelf bracket incorporating my new design;

FIG. 2 is a front elevational view thereof;

FIG. 3 is a top elevational view thereof;

FIG. 4 is a bottom elevation view thereof;

FIG. 5 is a back elevational view thereof; and,

FIG. 6 is a right side elevational view thereof, the left side being a mirror image thereof.
